Attorney

UNITED STATES PATENT OFFICE

MYRION TALBERT DICK, OF DES MOINES, IOWA

BLOTTING DEVICE

Application filed April 4, 1928. Serial No. 267,324.

The principal object of this invention is to provide a blotting device that readily absorbs liquid ink and the like from paper without smearing or blurring the ink on the paper.

6 A further object is to provide a blotting device that is operated by one hand.

A still further object of this invention is to provide a blotting device that may easily and quickly be refilled with new absorbent 10 material.

A still further object of this invention is to provide a blotting device that is noiseless in operation.

A still further object of this invention is 15 to provide a blotting device that will not mar or scratch a supporting surface upon which it may be resting.

A still further object of this invention is to provide a blotting device that is economical in manufacture, refined in appearance, and durable in use.

These and other objects will be apparent to those skilled in the art.

My invention consists in the construction, 25 arrangement and combination of the various parts of the device, whereby the objects contemplated are attained as hereinafter more fully set forth, pointed out in my claims and illustrated in the accompanying drawings, in 30 which:

Fig. 1 is a perspective view of my device ready for use.

Fig. 2 is a side sectional view taken on line 2-2 of Fig. 1, of my device and illustrates 35 the manner in which the rollers depress the blotter upon the ink to be absorbed.

Fig. 3 is an end sectional view of my device taken on line 3-3 of Fig. 2 and more fully illustrates its interior construction.

40 The use of a piece of absorbent paper for a blotter is not only unsightly after use, often difficult to find and pick up with the fingers, but requires two hands to operate. Such blotters fail to successfully absorb the wet ink 45 without blurring the penmanship. I have overcome these disadvantages as will be appreciated by those familiar with the art.

I have designated the frame or housing of my device by the numeral 10 having its bottom 50 open. Integrally formed on the mar-

ginal edge of each of the two longitudinal sides of the housing 10 is an inwardly extending flange 11, as shown in Figs. 2 and 3.

Loosely resting upon these two flanges, inside the housing 10 and inclosing the bottom thereof, is a sheet of absorbent material 13.

15 The cut-away portions 12 in each end of the housing 10 permits the entrance of the thumb and finger for the grasping of the absorbent material 13 for the easy removal or

the replacement of the same. This frame or housing is preferably made of light sheet metal and is of rectangular construction so that it may easily be placed over any character strokes that are adjacent the hinged

portion of a check book or the like. In order to hold the metal housing a slight distance

from the surface of furniture upon which it may be resting, I have provided a resilient supporting foot 14 such as rubber in each of

the four corners of the housing. These supports may be held in their respective places by cups 15 secured in each corner, or any other suitable means.

By this arrangement, the possibility of the device scratching or marring the varnish of the furniture is eliminated. Also, these resilient feet aid in preventing any movement of the housing relative to the paper to be blotted when the device is in operation.

The numeral 16 designates two parallel slots in the top of the housing 10 as shown in Figs. 1 and 3. The portion of the housing 10 between these two slots which is in the form of a flat bar is designated by the numeral 17.

Having its two ends extending into the housing through the two slots, respectively, and embracing the bar member 17 is the roller carrying member 18, U-shaped in cross-section.

Journaled in the two end portions of the member 18, spaced apart and transverse the longitudinal axis of the housing 10 are the two rods, 19 and 20. Around each of these rods is a roller 21 of suitable resilient material.

It should here be noted that each of the rollers are so positioned that they extend beyond the member 18, thereby being capable of engaging the two ends of the housing 10, respectively, when the member 18 is moved to

either end of the housing 10. By this arrangement, the resilient rollers act as bumpers and eliminate undesirable metallic noise. These resilient rollers also serve a similar function when the complete device is lifted by the member 18, by noiselessly engaging the bar member 17. The numeral 22 designates a handle member secured by suitable means to the roller carrying member 18.

10 To operate the device it is merely necessary to lift the same by the handle member 22 and place the housing 10 over the character strokes to be blotted and move the handle member 22 backwardly and forwardly relative to the 15 housing 10, thereby causing the resilient rollers 21 to roll upon the top surface of the absorbent material 13 and depress the same upon the wet ink to be blotted. The complete operation is noiseless and requires only one 20 hand.

There is no possibility or running or blurring the ink on the paper as the blotter is applied flatly to the same and the greater the downward pressure exerted on the handle 25 member 22, the more securely will the blotter be held against any creeping movement.

When the absorbent material 13 becomes too worn or soiled for further successful use, it may be easily removed in a moment's time 30 and a new blotter inserted.

Some changes may be made in the construction and arrangement of my improved blotting device without departing from the real spirit and purpose of my invention and it is 35 my intention to cover by my claims any modified forms of structure or use of mechanical equivalents which may be reasonably included within their scope.

I claim:

40 1. In a device of the class described, a housing open at its bottom, a flange formed on the lower marginal edge of said housing, absorbent material supported by said flange, and a means for exerting pressure on the top 45 surface of said absorbent material.

2. In a device of the class described, a housing open at its bottom, flanges formed on the lower marginal edge of said housing, absorbent material supported by said flanges, 50 and a means for exerting pressure on the upper surface of said absorbent material.

3. In a device of the class described, a housing open at its bottom, inwardly extending flanges formed on the lower portion of said 55 housing, blotting material resting on said flanges, a cutaway portion in said housing to facilitate the removal or replacement of said blotting material, and a means for exerting pressure on the top surface of said blotting 60 material.

4. In a blotting device, a housing open at its bottom, a means for holding a sheet of blotting paper in the bottom of said housing, non-metallic members secured to said housing 65 for holding said housing a slight dis-

tance from the supporting surface upon which it may be resting, and a means for exerting pressure on the upper surface of said blotting paper.

5. In a blotting device, a frame designed to hold a sheet of blotting paper, resilient feet members secured to said frame for holding the same a slight distance from the supporting surface upon which it may be resting and a means for exerting pressure on the upper 75 surface of said blotting paper.

6. In a blotting device, a one-piece housing member open at its bottom, inwardly extending flanges formed on the lower marginal edge of said housing, a sheet of absorbent material resting on said flanges and inclosing said bottom, said housing having a slot, a member extending through said slot, and a wheel member rotatably mounted on said last mentioned member, in said housing and capable of engaging the upper surface of said absorbent material.

7. In a blotting device, a housing member open at its bottom, an inwardly extending flange formed on the two opposite lower portions of said housing, blotting paper capable of being inserted into said housing and onto said two flanges, and a means for exerting pressure on the top surface of said blotting paper.

8. In a device of the class described, a housing open at its bottom, a sheet of absorbent material inclosing said bottom, said housing having a slot, a handle member extending through said slot, a resilient member secured to said handle member, in said housing and capable of engaging and depressing said absorbent material, and resilient members on said housing for holding the same a slight distance from the supporting surface upon which it may be resting.

9. In a device of the class described, a housing open at its bottom, inwardly extending flanges formed on the lower portion of said housing for supporting a sheet of absorbent material, said housing having two longitudinal slots, two rollers capable of traveling over the top surface of said absorbent material, and a handle member operatively connected to said rollers and extending through said slots.

10. In a blotting device, a housing open at its bottom, two inwardly extending flanges formed on the lower marginal edge of said housing and extending toward each other, a sheet of blotting paper inclosing said bottom, resting on said flanges and capable of being manually slid from said resting position on said flanges from said housing, said housing having two parallel slots, a bearing member embracing the portion of the housing between two said slots and extending into said housing, two roller members inside said housing and journaled in and between the two portions of the bearing member that ex-

tend into the said housing, and a resilient tube embracing each of said rollers; said rollers being so positioned on said bearing member that when the bearing member is reciprocated in said slots the resilient tubes will be capable of engaging the two ends of the housing, respectively.

11. In a blotting device, a housing open at its bottom, a sheet of absorbent material 10 inclosing said bottom, said housing having a slot, a handle member extending through said slot, a shaft rotatably mounted on said handle member and in said housing, a resilient tube embracing said shaft and so arranged and of such character that when said handle member is depressed it will engage the upper surface of said absorbent material and when said handle is lifted will engage the said housing and support the same, and 20 resilient feet members secured to said housing for holding the same a slight distance from the supporting surface upon which it may be resting.
